UNITED STATES PATENT OFFICE.

GEORGE N. HEIN, OF SAN FRANCISCO, CALIFORNIA.

WINDSHIELD CLEANER.

Application filed August 10, 1922. Serial No. 581,012.

To all whom it may concern:

Be it known that I, GEORGE N. HEIN, a citizen of the United States, residing at city and county of San Francisco and State of California, have invented certain new and useful Improvements in Windshield Cleaners, of which the following is a specification.

Pivottally mounted wind shield cleaners as at present manufactured, cover but a limited area of the wind shield and when in use render but a small portion of the shield in a condition to afford a driving or road sight opening. Cleaners are provided which move in a horizontal path across the shield, but the operation of this type of cleaner is difficult.

The present invention relates to an improved type of wind shield cleaner, wherein in a pair of fulcrumed arms are employed movable in an arcuate path and which are connected at their free ends by a conventional wiping element of the squeegee type. The operation of the arms causes a movement of the wiping element in an arcuate path while assuming a horizontal position and thereby operating over a considerable area of the shield. An object of this invention is to provide a type of structure, which is adapted for manual movement in one direction and automatical return movement in another direction, also to provide a structure wherein the pivoted arms are of approximately duplicate character and wherein an additional cleaning element is pivottally connected to one end of the main element and is in turn pivottally mounted at one end to swing in a path corresponding to that of its associated arm.

With the above mentioned and other objects in view, the invention consists in the novel construction and combination of parts hereinafter described, illustrated in the accompanying drawings, and set forth in the claims hereto appended; it being understood that various changes in the form, proportion and minor details of construction may be resorted to within the scope of the appended claims.

To more fully comprehend the invention, attention is directed to the accompanying drawings illustrating one embodiment thereof and wherein,

Figure 1 is a view in elevation of the wind shield cleaner mounted on a conventional vehicle wind shield and viewed from the interior of the vehicle.

Figure 2 is a view in detailed elevation of the cleaner in its normal position.

Figure 3 is a sectional view of a portion of a wind shield illustrating the mounting 60 for the supporting arms and in this embodiment illustrating the hand crank for operating the construction.

Figure 4 is a view similar to Figure 2 illustrating the wind shield cleaner in full 65 operative position.

Figure 5 is a view in elevation of the spring return arm illustrating the mounting plate therefor.

Figure 6 is a view in side elevation of the 70 arm illustrated in Figure 5.

Figure 7 is a view in side elevation of the cord guide secured to the wind shield frame.

Figure 8 is a view in plan of the same element and Fig. 9 is a perspective view of 75 the clamp for securing the cord to an operating pedal.

Referring particularly to the several views of the drawings wherein like characters designate corresponding parts, 1 indicates a vehicle wind shield rising from the cowl of a vehicle. To the horizontal top frame member 3 are secured at spaced intervals suitable attaching plates 4 outwardly from which extend the fulcrum 80 studs 5 on which are mounted the ends of the respective arms 6 adapted to swing in an arcuate path from a substantially horizontal position to a substantially perpendicular one. The free ends of the arms 85 6 are pivottally connected as at 7 by a channel bar 8 mounting the conventional form of rubber squeegee or wiping element 9, one end of the frame extending preferably beyond its point of fulcrum connection with 90 one arm 6. One of the plates 4, preferably that situated adjacent to the corner of the wind shield frame is formed on its lower edge with a horizontal slot 9' in which is adapted to slide the pin 10 carried by one 100 end of a secondary channel bar 11 which also mounts a conventional rubber squeegee or wiping element. The free end of the bar 11 is pivottally connected with the end of the bar 8 adjacent to the end of the arm 105 6 with which said bar 11 is associated. On the movement of the arms 6 by the operation of a hereinafter described mechanism it will be observed that the main wiping element moves in an arcuate path across the 110 shield while maintained in a horizontal position and that the secondary wiping ele-

ment due to being pivotally secured at one end, swings in an arcuate path from a substantially horizontal to a vertical position. This movement of the two elements clears 5 a relatively large area of the shield through which the operator may clearly view the road.

To return the arms to their normal position, I prefer to employ a tension spring 10 12 coiled at one end about the pin 5 extending from the plate slotted as at 9' and the terminal end of said spring is adapted for reception within one of a number of recesses 13 depending on the desired tension to be imparted to the spring. The opposite end of the spring 12 is maintained in contact with the arm 6 by a clamp or element 14 provided with an eye 15 to which is adapted to be secured one end of a flexible operating cord 16 which passes through 20 and operates within the guide opening 17 formed within the guide plate 18' secured to the wind shield frame. The opposite end of said flexible cord 16 is adapted for 25 attachment by means of a clamp 18 to one of the vehicle pedals or levers 19 or to any other suitable element adapted for operating by the operator of the vehicle. If desirable, the cord may mount a hand element 20.

Figures 2 and 3 illustrate an embodiment of the invention wherein the flexible cord element and spring 12 are eliminated and a hand crank 21 serves as a means for operating the wiper. 35

I claim:—

1. A wind shield cleaner including a pair of arms pivoted at corresponding ends to swing in arcuate paths, a horizontally disposed wind shield wiper pivotally connecting the free ends of said arms, a second wind shield wiper pivotally mounted at one end adjacent to the pivot point of one of said arms and disposed with its opposite end connected to one end of said first mentioned wiper and means for operating said arms. 40

2. A wind shield cleaner including two windshield wipers pivotally connected together at one end, means for supporting 50 their other ends means for simultaneously operating the same, one moving in an arcuate path from a substantially horizontal to a vertical position and the other in an arcuate path while maintained in a horizontal position. 55

In testimony whereof I have signed my name to this specification.

GEORGE N. HEIN.
